INVENTOR.
J. A. Shields!
BY J. E. Stebbins,
ATTORNEY.

UNITED STATES PATENT OFFICE

JOHN A. SHIELDS, OF AUBURN, CALIFORNIA

GRAPPLING HOOK

Application filed September 27, 1928. Serial No. 308,639.

My invention relates, generically, to a pair of grappling hooks adapted for use in connection with hoisting and conveying devices, such as steam shovels, derricks, cranes, etc., and, specifically, to a single hook provided with means for releasing the hook point when used alone or in combination with another similar hook.

The main object is the provision of a pair of hooks capable of engaging and holding objects or material of different sizes and irregular shapes, such as bowlders, logs, boxes, bales, etc.

Another object is the provision of one of said hooks when used in connection with another similar hook, or when used alone, with a locking and releasing device for the point of the hook.

The invention consists in certain novelties of construction and in the combinations of parts as herein set forth and claimed.

The accompanying drawing illustrates an example of the embodiment of the invention, the parts being constructed and combined according to the best modes of procedure I have so far devised for the purpose.

Figure 1 is a view in elevation of a pair of grappling hooks with connecting means, showing my invention as a whole.

Figure 2 is a projection or edge view of the hook at the right.

Figure 3 is a projection or edge view of the hook at the left.

Figure 4 is a side view in elevation of one of the removable and interchangeable steel points.

Figure 5 is a side view in elevation of the lever forming part of the point-locking and releasing means.

Figure 6 shows in side view a latch or trigger for the lever.

The bodies of the hooks are fashioned to curved shapes, such as arcs of circles, or parts of ellipses, or simple curves so the hooks can partly encircle an object to be grasped, and each hook may approximately be of a length equal to the radius which describes the curve.

The numerals 1 and 2 designates the bodies of the hooks. Each hook has an eye 3 through which loosely and slidingly passes a

chain or rope 4, the ends thereof being secured to a ring 5 adapted for connection with a suitable hoisting chain or cable.

The lower end of body 1 is slotted to receive a steel point 6 which is held in place by a threaded bolt 7 passed through the parts and secured by a nut.

The body 2 of the other hook has an elongated slot open at the lower end. Within this slot at its lower end is a steel point like steel point 6, and interchangeable therewith, pivoted through the medium of a threaded bolt 8 and nut so it can turn from the position shown in full lines to the position indicated by the dotted lines. To hold this point in operative position a lever 9 is pivoted within the slot by a pivot pin 10. The short arm 11 of the lever frictionally bears against the steel point at 12 and holds the point so it cannot rotate. The lever is held in locking position by a latch or trigger 13 pivoted at one end 14 within the slot and having a notch 15 which receives the end of the lever. This latch or trigger may have a hole 16 to receive an operating cord, and a projecting arm 17 to force the end of the lever outwardly when the trigger is raised and rotated.

Each steel point may have a curved bearing surface or seat at 18 and the lower end of the lever also has a curved surface at 19 to fit the said seat.

It will be noted that each steel point has an inner edge at 20 which is substantially radial to the curve of the body of the hook; that the long arm of the lever 9 is pivoted so as to move outwardly away from the object grasped by the hooks, and that the short arm of the lever cannot project around the inner curved line of the hook; and that the latch or trigger for the lever extends outwardly where it cannot come in contact with the object being grasped and raised by the hooks.

The hook 2 having the point-releasing means is adapted for use alone in some instances, as for dragging a log or raising an object, and when so used a cable or chain is to be secured in the eye 3, as is obvious.

The dotted lines in connection with the hook shown by Figure 2 illustrates the posi-

tions taken by the locking and releasing means when the load has been released.

The shapes of the bodies of the hooks, the disposition of a steel point relative to the inner curve of the body of the hook, and the disposition of the locking and releasing means for one of the hooks where its operation will not be interfered with by the object grasped by the hooks, are some of the important features of my invention.

10. What I claim is:

1. A hook having an eye at one end and a pivoted point at the opposite end and locking and releasing means for the point including a pivoted lever and a latch for the lever, said lever having an arm movable outwardly and away from the point.

2. A hook having an eye at one end, a slotted body portion, a point pivoted at the open end of the slot, a pivoted lever in the slot, the short arm of which bears against the point and prevents the latter's rotation, and a latch or trigger for the lever; said latch being pivoted to the body of the hook and having means for positively engaging and rotating said lever on its pivot.

3. The combination with two grappling hooks, each hook having a curved body portion with an eye at one end and a point disposed at an angle to the inner curved surface of the body portion at the opposite end, one of said points at the end of the curved body portion being rotatable relative to the body portion, and means in connection with the body portion for locking the point and releasing the same, of a chain or rope loosely and slidingly located within the eyes of the hooks, said chain or rope being adapted for attachment to an operating device.

4. The subject-matter of claim 3 wherein the means for locking and releasing the rotatable point includes a pivoted lever and a latch fixedly pivoted to the body of the hook.

5. The combination with two grappling hooks, each hook having a body portion with an eye at one end and a point at the opposite end, the inner edge of said point being on a radial line relative to the inner curved surface of the body of the hook, the point of one of said hooks being rotatable with means comprising a separately pivoted lever and latch for locking and releasing the point, of a chain or rope loosely and slidingly located within the eyes of the hooks, said chain or rope being adapted for attachment to an operating device.

6. The combination with two grappling hooks, each hook having a curved body portion with an eye at one end and a point disposed at an angle to the inner curved surface of the body portion at the opposite end, of means engaging the eyes of the hooks and adapted to pull them towards each other when said hooks engage a body to be lifted and the lifting power is applied; the point

of one of said hooks being rotatable, and said hook being provided with means in connection with the point for releasing the load from the point when in mid air and being acted upon by gravity.

7. A hook having a slotted shank with an eye at one end, a point pivoted to rotate at the opposite end of the shank, a lever separately pivoted within the slot the short arm of which engages the point and holds the point against rotation, and a latch or trigger pivoted to the shank and engaging the long arm of the lever.

In testimony whereof I affix my signature.

JOHN A. SHIELDS.
